US00D610567S

(12) **United States Design Patent**
Townsend

(10) **Patent No.:** **US D610,567 S**
(45) **Date of Patent:** **** Feb. 23, 2010**

(54) **HOUSING FOR A COMMUNICATION DEVICE BASE**

(75) Inventor: **David P. Townsend**, Lakewood, IL (US)

(73) Assignee: **Motorola, Inc.**, Schaumburg, IL (US)

(**) Term: **14 Years**

(21) Appl. No.: **29/299,813**

(22) Filed: **Jan. 4, 2008**

(51) **LOC (9) Cl.** **14-03**

(52) **U.S. Cl.** **D14/149**

(58) **Field of Classification Search** **D14/130, D14/137, 140, 140.1, 140.8, 141.1, 141.3, D14/142, 149-151, 158-159, 168, 171-172, D14/188, 211, 214, 225-226, 240, 243, 251, D14/253, 299, 336, 215, 167, 210, 212, 509, D14/140.4, 140.5, 140.6, 242, 140.2, 138 R, D14/144, 434, 148; 379/387.01, 388.02, 379/420.02, 447, 453, 434; 381/16; D13/107-108, D13/168; 455/351, 412.1**

(57) **CLAIM**

The ornamental design for a housing for a communication device base, as shown and described.

DESCRIPTION

FIG. 1 is a front perspective view of a housing for a communication device base.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.
